UNITED STATES PATENT OFFICE.

J. RAYMOND PLANK, OF GRAND RAPIDS, MICHIGAN.

FLEXIBLE SHAFTING.

1,036,144.

Specification of Letters Patent. Patented Aug. 20, 1912.

Application filed February 13, 1912. Serial No. 677,281.

To all whom it may concern:

Be it known that I, J. RAYMOND PLANK, a citizen of the United States of America, residing at Grand Rapids, in the county of 5 Kent and State of Michigan, have invented certain new and useful Improvements in Flexible Shafting; and I do hereby declare the following to be a full, clear, and exact description of the invention, such as will 10 enable others skilled in the art to which it appertains to make and use the same.

My invention relates to improvements in flexible shafting and its object is to provide a strong and durable structure which is inexpensive to manufacture and reliable in 15 operation, to provide a device that is easily repaired, and to provide the same with various new and useful features hereinafter more fully described and particularly pointed 20 ed out in the claims, reference being had to the accompanying drawings, in which:—

Figure 1 is an elevation of a device embodying my invention with portions broken away to show the construction; Fig. 2 an 25 enlarged detail of a number of the members forming the shaft proper; Fig. 3 an end elevation of one end of one of the said members; and Fig. 4 the same of the other end of the said member.

Like numbers refer to like parts in all of 30 the figures.

The shaft proper in my device consists of a series of movably connected members or links 1 adapted to operate out of alinement 35 and also to adapt the series to expand or contract longitudinally. This series is extended within the interior of a close coil 2 of wire and the coil inclosed within an outer casing 3 preferably a braided fabric.

The coil or wire and the fabric form no 40 part of my present invention, which is embodied in the sections forming the shaft proper, each section being of the general form of a prolate spheroid, the middle trans- 45 verse portion being solid and each end provided with connecting members whereby a series of the sections are movably connected with each other to permit elongation, contraction and bending of the complete structure as illustrated in Fig. 1. These sections

are formed at one end by providing a trans- 50 verse perforation as at 4, preferably rectangular, the outer portion or end of the section being provided with a transverse bar 55 or connecting member 7 of dimensions, transversely of the axis of the body, sub-

stantially the same as the distance between the jaws 5 on the other end and in the direction of the said axis of considerably less diameter. The jaws at the other end of 60 each section are formed with their opposite sides in planes parallel with the axis and spaced apart by substantially the width of the mortise or opening and the jaws are spaced apart from each other slightly more 65 than the width of the connecting bar 7. The thickness of this bar in the direction of the axis is considerably less than the width and the jaws to retain the same have inwardly-projecting shoulders 6 spaced 70 apart only enough to admit the connecting member 7 when the sections are turned substantially at right angles to each other and when the sections are turned in line or nearly so the inwardly-projecting shoulders 75 6 will engage the edges of the bar 7 and prevent the detachment of the sections and at the same time the sections will be free to swing relative to each other in the planes of the jaws and also have a limited relative 80 longitudinal movement. These jaws 5 at one end are in a plane at right angles to the direction of the mortise at the other end whereby the jaws swing alternately in planes at right angles at each coupling between the 85 series of sections.

Power applied to the first of the series of sections will rotate the entire series and at the same time each connection between the several members in the series enables the sections to operate successfully when turned out of alinement with each other separating longitudinally sufficient to prevent binding as the device is bent or curved, this separation being necessary because the close coil 90 95 cannot contract at the concave side and thus must expand at the convex side in order to bend as illustrated in the drawings.

It will be noted that in this structure, no pins or rivets are used; that the sections can be quickly and readily made by suitable forging dies, and provide a strong and reliable structure when in use. They also may be readily made of suitable castings, but I prefer steel forgings as stronger and more 100 105 satisfactory.

What I claim is:—

1. A flexible shaft, comprising sections having the general form of a prolate spheroid having a mortise in one end having opposite walls in planes parallel with the major axis of the section and jaws at the 110

other end having their opposite sides in planes parallel with the said axis and at right angles to the said planes of the mortise, said jaws being adapted to enter the 5 mortise in another section and longitudinally movable therein and also rotative therein about a transverse axis.

2. A flexible shaft, comprising a series of separable sections each having at one end a 10 transverse mortise or opening and at the other end a pair of jaws adapted to enter said opening and inwardly-projecting shoulders on the jaws movable longitudinally within said mortise and adapted to engage 15 the end wall of the opening and prevent detachment of the members and to pass the same and permit such detachment when the sections are turned substantially at right angles to each other.

20 3. A flexible shaft, comprising a series of separable sections each having at one end a mortise or opening therethrough, the end wall of the opening being of less diameter axially than transversely and jaws at the 25 other end having their opposite sides in planes at right angles to the direction of the said opening, said jaws being spaced apart

to permit said end wall to turn freely therein and move longitudinally thereof, and having inwardly-projecting shoulders spaced 30 apart and adapted to pass said end wall only when the sections are turned substantially at right angles to each other.

4. A flexible shaft, comprising a series of separable members each having the general 35 form of a prolate spheroid and provided at one end with a transverse rectangular mortise or opening having parallel opposite sides parallel with the axis of the section and jaws on the other end of the same having sides in planes parallel with the axis of the section and spaced apart to enter said mortise and also having inwardly-projecting shoulders to engage the end wall of the mortise in one position and to pass said wall in 40 another position and also to move longitudinally of the mortise when in the same.

In testimony whereof I affix my signature in presence of two witnesses.

J. RAYMOND PLANK.
